US00D346388S

United States Patent [19]

Silbernagel

[11] Patent Number: Des. 346,388

[45] Date of Patent: ** Apr. 26, 1994

[54] ARTICULATED SELF-PROPELLED
BI-DIRECTIONAL SOIL STABILIZER ROAD
RECLAIMER MACHINE

[76] Inventor: **Frederick J. Silbernagel**, 4007
Fontana Dr., Oklahoma City, Okla.
73116

[**] Term: **14 Years**

[21] Appl. No.: **808,446**

[22] Filed: **Dec. 16, 1991**

[52] U.S. Cl. **D15/22**

[57] **CLAIM**

The ornamental design for an articulated self-propelled bi-directional soil stabilizer road reclaimer machine, as shown and described.

DESCRIPTION

FIG. 1 is a perspective front view of an articulated self-propelled bi-directional soil stabilizer road reclaimer machine embodying my new design;

FIG. 2 is a rear perspective view thereof;

FIG. 3 is a top plan view thereof;

FIG. 4 is a right side elevational view thereof;

FIG. 5 is a front elevational view thereof;

FIG. 6 is a left side elevational view thereof; and,

FIG. 7 is a rear elevational view thereof.
